Primary Examiner — Jae Liang*(74) Attorney, Agent, or Firm* — Davis Wright Tremaine LLP; George C. Rondeau, Jr.**CLAIM**

The ornamental design for a lid for a beverage container, as shown and described.

DESCRIPTION

FIG. 1 is a top perspective view of a lid for a beverage container showing my new design.

FIG. 2 is a bottom perspective view thereof.

FIG. 3 is a front elevational view thereof.

FIG. 4 is a rear elevational view thereof.

FIG. 5 is a right side elevational view thereof.

FIG. 6 is a left side elevational view thereof.

FIG. 7 is a top plan view thereof; and,

FIG. 8 is a bottom plan view thereof.

The broken lines depict portions of the lid for a beverage container that form no part of the claimed design.
